UNITED STATES PATENT OFFICE.

JOHN A. LEWIS, OF OARK, ARKANSAS.

DELIVERY APPARATUS.

1,201,206.

Specification of Letters Patent. Patented Oct. 10, 1916.

Application filed February 23, 1916. Serial No. 80,011.

To all whom it may concern:

Be it known that I, JOHN A. LEWIS, citizen of the United States, residing at Oark, in the county of Johnson and State of Kansas, have invented new and useful Improvements in Delivery Apparatus, of which the following is a specification.

This invention relates to delivery apparatus and it consists in the novel features hereinafter described and claimed.

The primary object of the invention is to provide an apparatus of simple and durable structure especially adapted to be used for delivering mail although the apparatus may be used to advantage for delivering light articles as for instance merchandise, meals, household supplies and the like.

With this object in view the apparatus comprises a cable supported at an elevated position with relation to the ground and having bumper mechanisms located at the terminal ends thereof. A car or carrier is mounted to travel upon the cable and may be operated by a spring motor or an electric motor as desired. In the arrangement as shown in the drawings, the car is propelled by an electric motor and two systems for moving the car along the cable are shown and described.

In one system, the source for generating the current is carried by the car and is transmitted to the motor which is also carried by the car. Means are provided for propelling the car from the motor. In the other system, the source of electric supply is connected with an overhead wire and the cable and the said source is located at a fixed point. A motor is carried by the car and the electric current is transmitted to the motor through a trolley arm and wheel in the usual manner. The motor is operatively connected with one of the supporting wheels of the car, the said wheel being mounted to travel along said cable.

As illustrated in the accompanying drawing: Figure 1 is a side elevation showing the arrangement of parts when the source of power is carried by the car. Fig. 2 is a similar view showing the arrangement of parts when the source of power is located at a fixed point. Fig. 3 is a longitudinal sectional view of the car shown in Fig. 1. Fig. 4 is a detailed sectional view of a pole changer used on the car. Fig. 5 is a longitudinal

sectional view of a portion of the car shown in Fig. 2. Fig. 6 is a transverse sectional view of the same.

As illustrated in Fig. 1 of the drawings, the system includes poles 1 which are mounted in the ground at suitable intervals apart and which are provided at their upper portions with brackets 2. A track cable 3 is supported upon the brackets 2 in the usual manner. Bumper posts 4 are located at the ends of the cable 3 and the ends of the said cable are connected with the said posts in any suitable manner. Arms 5 are mounted at the upper ends of the posts 4 and bars 6 are pivotally connected at their upper ends with the said arms 5. Springs 7 are interposed between the intermediate portions of the bars 6 and the adjacent sides of the posts 4 and are under tension with a tendency to normally hold the lower or free ends of the bars 6 spaced from the adjacent sides of the posts 4. Loops 8 loosely surround the intermediate portions of the bars 6 and adjacent posts 4 and serve to limit the swinging movement of the lower portion of the bars 6 in directions away from the intermediate portions of the posts. Keepers 9 are mounted at the lower end portions of the bars 6. Arms 10 are mounted upon the terminal poles 1 and are disposed at angles with relation to the same. Upstanding lugs 11 are carried at the outer ends of the arms 10.

The car or carrier 12 is in the form of a box or receptacle which is divided at a point between its ends by a partition 13 into compartments. In one of these compartments the articles to be carried may be placed while the other compartment contains the motor and source of electric supply. The motor 14 is of usual pattern and a pulley 15 is journaled upon the shaft thereof. A bracket 16 is connected with the top of the car or carrier 12 and wheels 17 are journaled to the said brackets and are adapted to travel upon the track cable 3. A pulley 18 is formed on the bracket and a belt 19 is trained around the pulleys 15 and 18. A bar 20 is mounted upon the top of the car or carrier 12 and its end portions project beyond the ends of the body of the said car or carrier. Spring catches 21 are mounted upon the upper side of the bar 20 at the ends thereof and are adapted to engage the keepers 9 when the ends of the bar 20 come

in contact with the lower portions of the bars 6 as will be hereinafter explained. Batteries 22 are mounted upon the car or carrier 12 and electric wires 23 connect the 5 batteries 22 with terminals positioned adjacent the path of movement of the upper end of a switch 24 located at the end of the car or carrier 12. The lugs 11 are located in the path of movement of the lower end of 10 the switch 24 and when the switch comes in contact with the said lugs, the switch is moved whereby the upper end of the switch is carried out of engagement with the terminals at the ends of the wires 23. Wires 25 15 are connected one with the motor 14 and the other with a spring terminal 25'. They are also connected with terminals located adjacent the switch 24. A terminal 24' is located on the bar 20 below the free end of 20 the terminal 25' and a wire 23' connects the terminal 24' with the motor 14. When the switch 24 is in contact with all of the terminals at the ends of the wires 23 and 25 and the terminal 25' is in contact with the 25 terminal 24' an electric circuit is established from the batteries 22 to the motor 14 and when the motor is operated through the pulley 15 and belt 19 the pulley 18 is rotated. Trains of gear wheels 18' connect 30 the shaft of the pulley 18 with the wheels 17 whereby the said wheels are rotated to cause the car or carrier to move along the track 3. The switch 24 is of the pole changer type and hence the switch may be manipulated 35 to cause the current to travel from the batteries 22 to the motor 14 in a desired manner to cause the motor to propel the car along the track cable 3 in either of two directions.

Assuming the apparatus described is intended to transport mail from a residence to 40 a point at the side of the route over which the mail carrier travels, the mail is placed in the compartment of the car or carrier 12 at the opposite side of the partition 13 from that side at which the motor 14 and batteries 22 are located. An operator then 45 adjusts the switch 24 whereby the current is caused to travel from the batteries 22 over the wires 23 and 25 to the motor 14 in the proper direction and the motor through the connecting pulleys and belt propels the car or carrier 12 from the residence to the point adjacent the side of the route along which the mail carrier travels. When the mail 50 carrier arrives at the car or carrier he removes the mail therefrom and places in the car or carrier any mail which is intended to be delivered at the said residence. When the car arrives at the side of the mail route, 55 the lower portion of the switch 24 strikes the upstanding lug 11 whereby the switch is turned and the electric circuit from the batteries 22 to the motor 14 is broken. The car then continues to move toward the terminal posts 4 under the momentum that it

has gained and when the end of the bar 20 strikes the lower end of the bar 6, the spring 7 is compressed whereby the car is cushioned as it is brought to a state of rest. Just after the end of the bar 20 strikes the lower end of the bar 6 the spring catch 21 at the upper side of the bar 20 engages over the keeper 9 and the car or carrier 12 is held adjacent the terminal post toward which it has been traveling. After the mail carrier removes the mail from the car or carrier 12 and deposits the mail therein which is to be delivered he manipulates the switch 24 to cause the current to travel in a proper manner from the batteries 22 to 70 the motor 14 then releases the catch 21 from the keeper 9 and the car moves back toward the residence. When the car arrives at the residence one end of the bar 20 strikes the lower end of the bar 6, the catch engages 75 the keeper 9 and the switch 24 is turned as hereinbefore described and the car comes to a state of rest at the point where the mail is to be delivered.

In the arrangement of parts as shown in Fig. 2 of the drawing, a current wire 26 is supported above the track cable 3, and batteries 27 are located at a fixed point instead of being carried by the car or carrier as hereinbefore described. Wires 28 connect 90 the batteries 27 with the wire 26 and the track cable 3. A trolley arm 29 is mounted upon the car or carrier 12 in the usual manner and a trolley wheel 30 is journaled at the upper end thereof and is adapted to 95 travel along and in contact with the current wire 26 in the usual manner. A wire 31 is connected at one end with the wheel 30 and at its other end with the motor 14. A wire 32 is connected at one end with the motor 14 and at its other end with the bracket 16 which through the supporting wheels 17 is 100 electrically connected with the track or cable 3, when the terminal 25' is in contact with the terminal 24'. The switch 24 is adapted to 105 operate with terminals provided at the end wires 31 and 32 in a manner similar to the switch shown and described in the arrangement shown in Fig. 1 of the drawing. In 110 this form of the invention it will be seen that the car or carrier 12 may be propelled in either of two directions along the track or cable 3 and an operator may disconnect either one of the wires 28 from the battery 27 whereby the said car or carrier 12 may 115 be caused to come to a state of rest at a point between the terminal posts of the system. Also by reversing the connection between the wires 28 with the poles of the batteries 27, the said poles may be changed 120 whereby the car or carrier 12 may be caused to move in either direction of two directions along the track or cable 3.

While the two systems hereinbefore described employ electric motors for propelling 130

ling the car or carrier it is to be understood that these motors may be substituted by spring motors which are operatively connected with the propelling wheels in a manner the same as that described in connection with the arrangement shown in Figs. 1 and 2 of the drawings.

In both forms of the invention a governor 40 is mounted on the shaft of the pulley 18 and the weighted arms 41 of the said governor bear against a piece 42 slidably mounted on the governor 40. A lever 43 is fulcrumed in a yoke 44 mounted on the bar 20 and one end of the said lever is attached 15 to the terminal 25' while the other end bears against the piece 42. A spring 45 connected at one end with the lever 43 and at its other end with the yoke 44 serves to hold the lever in contact with the piece 42. Brake 20 levers 46 are pivoted on the shafts of some 25 of the wheels 18' and have ends adapted to engage the peripheries of the wheels 17. Links 47 connect the inner ends of the levers 46 with the lower end of the lever 43. In the event that the rate of speed of travel of 30 the car becomes excessive the arms 41 are swung in an outward direction under centrifugal force and the piece 42 is moved in an outward direction whereby the lever 43 is swung and the contact 25' is lifted out of 35 engagement with the terminal 24' and the electric circuit to the motor is broken. At the same time the links 47 swing the levers 46 whereby their ends come in contact with

the peripheries of the wheels 17 and serve 35 as brakes to bring the car to a state of rest.

From the above description taken in conjunction with the accompanying drawing it will be seen that an apparatus for delivering articles is provided and the structural arrangement of the apparatus is simple and durable and may be easily and quickly manipulated for causing the car or carrier which contains the articles to move in either of two directions along the supporting track or cable.

Having thus described the invention, what is claimed is:

A delivery apparatus comprising a cable supported in elevated position, posts mounted at the ends of the cable and connected to the same, bars pivotally connected with the posts, springs in the posts between the bars and the posts, loops loosely surrounding the bars and the posts, keepers carried by the 55 said bars, a car mounted for movement along the cable, means for propelling the car, a bumper bar carried by the car and engageable with the first mentioned bars, and spring catches mounted upon the bumper 60 bar and adapted to engage the keepers.

In testimony whereof I affix my signature in presence of two witnesses.

JOHN A. LEWIS.
